WINDBREAK AND SECURING MEANS THEREFOR

Filed March 3, 1928

FIG. 1.

FIG. 2.

FIG. 3.

INVENTOR.
JOSEPH LEDWINKA.

BY *John P. Tarbox*
ATTORNEY.

UNITED STATES PATENT OFFICE

JOSEPH LEDWINKA, OF PHILADELPHIA, PENNSYLVANIA, ASSIGNOR TO EDWARD G. BUDD MANUFACTURING COMPANY, OF PHILADELPHIA, PENNSYLVANIA, A CORPORATION OF PENNSYLVANIA

WINDBREAK AND SECURING MEANS THEREFOR

Application filed March 3, 1928. Serial No. 258,701.

My invention relates to windbreaks and means for securing them to the edges of door and window openings of vehicle bodies.

It is an object of my invention to provide a windbreak which can be readily and cheaply manufactured and to provide means for securing it positively in place which requires a minimum of fastening devices.

I attain this object generally by forming 10 the edge of the windbreak which overlaps the frame member at the edge of the closure opening with a longitudinal enlargement or beaded portion which coacts with a longitudinal recess formed adjacent the edge of said 15 frame member or in the edge of a trim panel applied to the inside of said frame member and overlapping the inner beaded edge portion of said windbreak to lock the latter securely in place when the trim panel is secured 20 in place without the necessity of additional securing means for the windbreak.

In the accompanying drawings, and in the detailed description following, I have illustrated a specific embodiment of my invention 25 and its application to a double walled sheet metal body of the type disclosed in my application Serial No. 159,827 for pressed metal vehicle body, filed January 8, 1927 for use on which it is very well adapted, but it will 30 be understood that it is also applicable to other types of bodies.

In the drawings, Fig. 1 represents in side elevation a body of the type shown in the above referred to application, to which I have 35 shown my invention applied.

Fig. 2 is a detail sectional view taken approximately on the line 2-2 of Fig. 1 through the B-C post of the body.

Fig. 3 is a perspective view of a short 40 length of my improved windbreak.

The body to which I have shown my invention applied is of the sedan type and consists in large part and particularly around the door and window openings, as represented, 45 the front door opening 10, the rear door opening 11 and the rear quarter window 12, of outer and inner sheet metal panels. These panels are joined together in the margins of the door and window openings by crimping 50 the edge of one over the edge of the other,

and form the frame surrounding said openings.

The invention is herein shown only as applied to the B-C post of the body but its application to other parts of the body will be 55 apparent from this single illustration of its application.

As shown in Fig. 2, the B-C post proper which constitutes the vertical frame member rising between the front and rear door 60 openings 10 and 11, comprises the outer sheet metal panel 13 and the inner sheet metal panel 14, the outer panel being of inwardly presenting channel form, the side walls 15 and 16 of which provide the jamb faces of 65 the adjacent door openings. At their inner edges the side walls 15 and 16 are provided with lateral flanges 17 and 18 and to these flanges are crimped the edges 19 and 20 of the substantially flat inner panel 14. To form 70 a secure locked crimped joinder the inner panel is formed adjacent its edges with longitudinal recesses or depressions 21 and 22 which provide shoulders 23 and 24 on the outer side of the panel which abut the side 75 walls 15 and 16 of the outer panel stamping. I make use of these depressions or recesses, for rigidly securing my novel improved wind break in place.

This wind break consists, as shown, in Figs. 80 2 and 3, of a flexible strip 25 provided with a yielding compressible enlarged or beaded portion 26 on one side or edge thereof and a relatively unyielding enlarged or beaded portion 27 preferably of smaller diameter than 85 the first, along the other edge thereof, the intermediate portion 28, connecting the beaded edge portions being of less thickness than the edges.

In the embodiment of my invention 90 shown, I form the enlarged edges and the web connecting them, of a strip of upholstery fabric 29, the edges of which are formed into loops 30 and 31, by turning over the edges 95 of the loops and stitching them to the body of the strip inwardly of said edges.

One of these loops, I make larger than the other, and provide the desired yielding or resiliency by filling it with a compressible filler such as the rubber tube 32, and the other loop, 100

I fill with a relatively unyielding or non-compressible substance, such as the cord 33.

The windbreak, so constructed, is adapted to cooperate very effectively with the depressions 21, 22 formed in the post adjacent the edges of the door openings and with the relatively rigid trim panel 34, secured to the inner side of the inner panel 14, to cover the post on the inside, as by the clamping cups 34, secured by drive screws, and covered by the finishing button 35 snapped into the cup in the manner fully disclosed and claimed in my prior application Serial No. 231,551, filed November 7, 1927, for device for attaching moulding or by any other suitable fastening means.

The trim panel may be formed with a relatively rigid core 36, such as wood or composition board, which is covered by suitable upholstery fabric 37, and when the parts are assembled, the relatively unyielding or non-compressible inner beaded edge portions 27 of the windbreaks are seated in the recesses 21 and 22, the reduced intermediate portions 28 are clamped between the outer edge portions of the trim panel 34 and the slightly outwardly offset edge portions 38 and 39 of the posts outwardly of said recesses, and the outer enlarged and relatively yielding beads are located in a position where they are engaged by the edge of the front and rear doors or closures indicated in dotted lines at 40 and 41, and because of their yielding construction are adapted to lie snugly against the edges of the doors and fill up any irregularity, if such there be, so as to very effectively exclude the rush of air between post and door into the interior of the body.

The relatively unyielding inner beaded edge portions 27 of the windbreaks are held in the recesses 21 and 22 without any special securing means, and positively retained in position by the relatively rigid trim panel 39, securely held against withdrawal therefrom not only by the clamping action of the outer edge portions of the panel upon the reduced intermediate portion 28, but also more particularly by the fact that to withdraw the bead from the recesses, it would be necessary to flex the relatively rigid trim panel edges inwardly a substantial distance. Such flexing of the trim panel opposes by reason of its relative rigidity. In fact, the windbreak is securely held in position by the improved construction, if there is no clamping action on the intermediate reduced portion 28.

While I have herein described a specific embodiment of my invention, it will be understood that various changes and modifications may be made without departing from the spirit and scope of the invention as expressed herein and in the appended claims.

What I claim is:—

1. In a vehicle body, a frame member arranged at the edge of a closure opening and

having the main body of its inner surface relatively plane, but formed with a longitudinal recess adjacent the edge of the opening and a slightly offset portion extending from said recess to the edge of the opening, a windbreak having an enlarged edge portion seated in said recess and an intermediate body portion seated against said offset portion and having its opposite edge portion extending into the closure opening, and a trim member applied and secured against the inner surface of said frame member and having its edge extended substantially to the edge of said frame member adjacent said opening, said trim member and frame member cooperating to securely clamp the windbreak in position against longitudinal and lateral displacement.

2. In a vehicle body, a frame member forming the edge of a closure opening, and having its inner wall formed with a longitudinally extending recess adjacent said opening, a relatively rigid trim member applied and secured to the inner side of said frame member and extending over said recess, and a windbreak having a beaded inner edge of relatively unyielding character secured in said recess by said trim member and having its opposite edge formed with a relatively yielding beaded portion extending into the closure opening.

3. In a vehicle body, a frame member arranged at the edge of a closure opening, said frame member being provided with a depression arranged adjacent to and extending longitudinally along one edge thereof, a substantially flat upholstery trim member secured to the inner side of said frame member and adapted to form conjointly with said depression a longitudinally extending recess, and a windbreak having relatively compressible and incompressible enlargements along opposite edges thereof, said windbreak being securable in position with the incompressible enlargement thereof clamped within said recess and the compressible enlargement projecting into said closure opening.

4. In a vehicle body, in combination, a frame member arranged at the edge of a closure opening, said frame member being provided in the inner side thereof with a depression arranged adjacent to and extending longitudinally along one edge thereof, a windbreak member formed with a relatively incompressible bead along one edge thereof, said depression being adapted to receive said bead, and a relatively rigid upholstery trim member arranged for securing to said inner side of the frame member and adapted to overlie said depression whereby to securely clamp said bead therewithin against lateral and longitudinal displacement.

5. In a vehicle body, a frame member arranged at the edge of a closure opening, a trim member secured against the inner face

of said frame member, said members being complementally formed to provide a longitudinally extending recess therebetween, and a windbreak having an enlarged edge portion adapted to be clampedly retained within said recess against lateral and longitudinal displacement by said members, the opposite edge of said windbreak projecting freely from between said members into said closure opening for cooperation with a closure.

6. In a vehicle body, in combination, a vertically extending frame member of substantially inwardly presenting channel formation, a panel secured to and extending between the inner edges of said frame member, the body of said panel being laterally offset to provide a pair of longitudinally extending laterally spaced seats, a pair of windbreaks each having relatively incompressible longitudinally extending beaded edges respectively arranged to be received within said seats, and a relatively rigid upholstery trim member secured to said panel with the opposite edges thereof overlying said seats whereby to clamp said beaded edges therewithin against lateral displacement therefrom, the opposite edges of said windbreaks projecting freely beyond the opposed edges of said trim member and being in the form of relatively compressible beads.

7. In a vehicle body, an outer panel forming the outer side of a doorway frame member and flanged inwardly at the doorway opening to substantially the full depth of the doorway opening, an inner panel secured to the inner edge of said outer panel at the doorway opening to form therewith a hollow frame structure, said inner panel being formed adjacent the margin of the doorway opening with an inwardly opening recess extending longitudinally of the frame member, and means associated with said inner panel and extending across the mouth of said recess to secure and retain a trim part.

45 In testimony whereof he hereunto affixes his signature.

JOSEPH LEDWINKA.
